(57) **CLAIM**

The ornamental design for a leg for a raised garden, as shown and described.

DESCRIPTION

FIG. 1 is an isometric view of the leg for a raised garden; FIG. 2 is an isometric view of the leg for a raised garden in another orientation;

FIG. 3 is a front isometric view of the leg for a raised garden;

FIG. 4 is a back isometric view of the leg for a raised garden;

FIG. 5 is a front view of the leg for a raised garden;

FIG. 6 is a back view of the leg for a raised garden;

FIG. 7 is a right side view of the leg for a raised garden;

FIG. 8 is a left side view of the leg for a raised garden;

FIG. 9 is a top view of the leg for a raised garden; and,

FIG. 10 is a bottom view of the leg for a raised garden.

The broken lines in the drawings depict environmental subject matter only and form no part of the claimed design.
